UNITED STATES PATENT OFFICE

EDWIN M. WYATT, OF MADISON, WISCONSIN, ASSIGNOR, BY MESNE ASSIGNMENTS, TO AMERICAN FACE BRICK RESEARCH CORPORATION, A CORPORATION OF ILLINOIS

TEXTURED BRICK

Application filed December 17, 1928. Serial No. 326,516.

This invention relates to certain new and useful improvements in textured brick.

In the process of manufacturing brick by extruding the plastic clay through a die and then cutting the extruded column into individual bricks, it is frequently the custom to treat the advancing column to some form of texturing process to increase the beauty of the resulting bricks which are usually cut off or severed from the column after the texturing operation. As a result of this method of texturing the bricks, it is the customary practice to perform the texturing operation on three faces only of the advancing column, the fourth or under face of the column being supported from below in such a way as to prevent contact with a texturing appliance, with the result that after the individual bricks are severed from the column they display a textured surface on three of the edge faces and remain untextured on the fourth edge face and on the broad faces which represent the planes of severance from the column, according to the common practice.

In the building of brick walls, a practice has recently developed of setting some of the bricks in position to expose their broad faces to the wall surface, for the purpose of introducing a pleasing variation in the appearance of the completed wall, and also for the purpose of creating air spaces within the wall, that keep the interior dry and better insulated and also result in saving of labor and material. Where this practice has been followed, the bricks employed have been untextured, generally known as "common" bricks. Obviously, textured bricks, commonly known as "face" bricks, cannot be used in such a wall unless they are textured on at least that broad face which is exposed in the wall surface.

The brick of the present invention is designed to meet the requirement of affording a face brick which is textured on one of its broad faces, generally a face afforded by the severing of the clay column. Such a brick may be used with advantage in wall construction in which the practice is observed of

presenting the broad faces of the bricks to the exterior of the wall.

The method of producing such bricks forms no part of the present invention, but constitutes the subject matter of a co-pending application filed concurrently herewith. However, the method of producing the present type of brick may be briefly defined as follows: The brick column is extruded through a die in the usual way, and while advancing under the impetus from behind is severed in sections in the usual manner. These sections are afterwards upset or overthrown by suitable means to present one of the broad severed faces of the brick to the action of a texturing tool or appliance, so that a proper finish is given to a surface which under the common practice is unexposed to the action of the texturing tool, although the broad face might be otherwise textured either during or after the extension process.

In the drawings:

Figure 1 is a perspective view of the brick of the present invention, showing two of the edge faces textured in the customary manner, and the broad top face also textured in conformity with the principles of the present invention;

Fig. 2 is a perspective view taken from a diagonally opposite position, showing the opposite edge textured and the rear edge untextured; and

Fig. 3 is a perspective view, showing another form of texturing, in which the texturing assumes a form of undulating lines or corrugations.

The brick of the present invention is preferably of the present United States standard dimensions of two and one-fourth by three and three-fourths by eight inches (popularly spoken of as two by four by eight), although obviously the present invention is not limited to bricks of these substantial dimensions. As shown, the brick is preferably textured on each edge A and B, Fig. 1, and on the front side edge C, the rear side edge F being left untextured. This is the common characteristic of face brick, which, however, is untextured on a broad eight by four face, usually the ones produced by severing of the

clay column. The present brick is also textured on at least one of the broad faces E, in Fig. 1, although untextured on the other broad face D, and also untextured on the rear edge F of the near edge in Fig. 2. This affords a brick which can be used either in standard brick-laying with one of the edges or one of the ends exposed in the brick-work, and also enables the brick to be used in the special wall construction in which the broad side or face of the brick is exposed.

As shown in Figs. 1 and 2, the texturing lines are in the form of grooves with intervening ribs or corrugations, the ribbing being in parallel straight lines running crosswise of the surfaces on which the texturing appears, but the form or design of the texturing may be modified to present wavy or undulating corrugations, as in Fig. 3, or any other grooving or marking which is commonly employed in the texturing of brick to improve its appearance.

As shown, the texturing assumes the appearance of transversely running corrugations, by reason of the fact that the texturing is preferably formed by moving the brick sections, while in plastic condition, past a stationary texturing tool of comblike formation, where a straight line texturing is desired, or past a comblike texturing tool which is reciprocated transversely of the line of travel of the brick sections, where undulations are desired. However, it is not the intention to limit the invention to a texturing or surfacing ornamentation, which necessarily assumes the appearance of grooves or corrugations, since other designs may obviously be applied by appropriate methods without departing from the spirit of the present invention.

Although the texturing of at least one of the broad surfaces is intended primarily to enable the brick to be advantageously employed in a wall in which some or all of the bricks are laid to expose their broad faces, the provision of a roughened broad surface, occasioned by the texturing operation, is of advantage in the bonding of the bricks, even where laid flatwise, since the roughened surface affords a better anchorage for the mortar.

The brick of the present invention is one which is peculiarly adapted to the requirements of present day brick-laying in which variations in the arrangement of the courses are frequently employed for the purpose of increasing the variety and design in the brick-work, which is desirable in order to vary monotony in appearance and to realize in full the decorative possibilities of brick construction.

I claim:

1. As a new article of manufacture, a clay brick of standard dimensions adapted to present various exposures and comprising two

broad oblong rectangular faces, two short and narrow end edges and two long and narrow side edges, and having one of its broad faces produced by severing and then textured to improve the appearance of the surface, and having its two end edges and one of its side edges also textured.

2. As a new article of manufacture, a clay brick of standard dimensions adapted to present various exposures and comprising two broad oblong rectangular faces, two short and narrow end edges and two long and narrow side edges, and having one of its broad faces produced by severing and then textured to improve the appearance of the surface, and having its two end edges and one of its side edges also textured, the texturing in each instance being in the form of parallel corrugations extending in each instance in the direction of the short dimension of the textured surface and crosswise thereof.

In witness that I claim the foregoing I have hereunto subscribed my name this 11th day of December, 1928.

EDWIN M. WYATT.
